PILE FABRIC

Application filed March 28, 1931. Serial No. 525,966.

This invention relates to pile fabrics and more particularly to carpets or rugs having the pattern visible at the back.

It is well known that in oriental rugs the pattern upon the face of the rug is also visible at the back, and there is more or less demand for domestic or machine made rugs constructed so that the pattern is visible at the back.

Machine made rugs and carpets having the pattern visible at the back have been manufactured heretofore, but when the pile forming yarns are carried through to the back of the fabric to cause the pattern to show at the back the length of yarns required to form the pile loops is increased, thus increasing the cost of the fabric, and the difficulty of securing the pile forming loops to the fabric is increased when the base of the loops are exposed at the back instead of resting upon the woven structure.

Having in mind the foregoing the present invention contemplates a novel form of pile fabric having the pattern visible at the back, and which is simple in construction, is well bound and easy to weave, and requires a minimum amount of yarn to produce the pile loops.

The fabric of the present invention is a two plane fabric having all the stuffer or filler warps in a single plane, and the pile forming yarns are looped about a weft below the stuffer warps and are supported at their opposite sides by wefts positioned above and below the stuffer warps. As a result of this construction in which all stuffer warps lie in a single plane the thickness of the ground fabric is reduced and a corresponding saving is secured in the length of pile forming yarns required to extend through to the back of the fabric. Furthermore the diagonally disposed wefts engaging the opposite sides of the pile loops serve to hold the pile forming tufts firmly in place.

The various features of the invention will be further understood from the following description when read in connection with the accompanying drawings illustrating one good practical embodiment of the invention.

In the drawings:

Fig. 1 is a plan view of the face of a piece of pile fabric constructed in accordance with the present invention.

Fig. 2 is a view of the back of the fabric of Fig. 1 showing the pattern upon the back.

Fig. 3 on an enlarged scale is a longitudinal sectional view of the fabric of Fig. 1; and

Fig. 4 is a transverse sectional view of the fabric of Fig. 3.

The pile fabric of the present invention may be readily woven on the ordinary Axminster loom, and is illustrated in the drawings as formed of the stuffer or filler warps 10 and 11, the chain warps 12, the upper wefts 13 and the lower wefts 14 and 15. The stuffer warps 10 and 11 all lie in the same plane and extend lengthwise of the fabric in a straightened condition as shown, and the upper and lower wefts 13, 14 and 15 are firmly bound to the opposite faces of the stuffer warps 10 and 11 by the chain warps 12.

The fabric illustrated is a two plane weave having three shots to the complete cycle, there being two wefts below the stuffer warps for each weft above these warps, and the chain warps 12 pass alternately over an upper weft 13 and under the lower wefts 14 and 15.

The pile forming yarns 16 are looped about a lower weft 15 as shown, and the other lower weft 14 rests against one face of the row of pile yarns extending across the fabric, while the upper weft 13 is positioned at the opposite side of this row of pile yarns or tufts. The arrangement is such that the wefts 13 and 14 are disposed diagonally to each other and bend somewhat the portions of the pile loops lying between them as will be apparent from Fig. 3, the results being that the pile forming loops are firmly secured to the ground fabric and the base of the loops are exposed at the back of the fabric to produce the pattern on the back.

The stuffer or filler warps 10 and 11 are relied upon to provide the longitudinal strength of the fabric and are therefore formed of cotton or other relatively strong material. A single stuffer warp may be employed between each pair of tufts 16, but in

the construction shown two warps 10 and 11 are provided one being laid at each side of the chain warp 12 as this binds the pile tufts 16 more firmly in place than would a single stuffer warp.

The pile forming yarns 16 may be delivered to the fabric by tube frames or nippers such as commonly employed upon Axminster looms, and in the construction shown each 10 weft 13, 14 and 15 is formed of two threads laid by the in and out travel of the needle and constitutes what is commonly called a shot of weft.

In weaving the present fabric either two 15 or three frames or harnesses may be employed depending whether one or two stuffer warps are laid between each row of tufts. In weaving the construction shown one frame is needed for the chain warps 12, and if a 20 second frame is provided for the stuffer warps 10 and a third frame for the stuffer warps 11, the frames for the warps 10 and 11 are moved together. It will therefore be seen that the weaving operations required to 25 produce the present fabric are extremely simple and that no extra gearing is required to operate the harness cams.

When the fabric of the present invention is woven on a needle type of loom so that 30 each weft is formed of two threads, as shown, a further advantage is secured since the two threads of the upper weft 13 will be held by the chain warps side by side horizontally as shown, while the two threads of each lower 35 weft 14 and 15 will be held side by side vertically as shown, and as a result the horizontal arrangement of the two upper threads 13 tends to take up the space between the adjacent rows of tufts, while the vertical arrangement of the two threads forming each weft 40 14 and 15 increases their binding action upon the row of tuft yarns and causes the base of the loops of the yarns 16 to show up with increased clearness at the back of the fabric. The arrangement of the weft forming threads just described results from the fact 45 that the upper yarns are held by the chain warps 12 against the stuffer warps at the 50 time the beat up of the lay occurs, while the lower wefts which are beaten up in the same shed are not held by the chain warp while beaten up and therefore are free to take the vertical position as shown.

The weave of the present invention possesses a further advantage in that in the present construction the operation of bending or turning up the pile forming yarns about the weft 15 is easy to perform.

It will be seen from the foregoing that a 60 pile fabric constructed in accordance with the present invention is easy to weave and that the parts thereof are firmly bound together, and that a saving in the length of 65 pile yarn required to extend through to the

back of the fabric is secured by employing a two plane weave.

What is claimed is:—

1. A pile fabric having the pattern visible at the back and formed of stuffer warps all 70 laid in a single plane, wefts laid above and below the stuffer warps and arranged with twice as many wefts below the stuffer warps as above them, a row of pile forming yarns looped about one of a pair of lower shots of 75 wefts, and chain warps passing alternately around one upper shot of weft and two lower shots of wefts.

2. A pile fabric having the pattern visible at the back and formed of stuffer warps all 80 laid in a single plane, wefts laid above and below the stuffer warps and arranged with twice as many wefts below the stuffer warps as above them, a row of pile forming yarns looped about one of a pair of lower wefts, 85 and chain warps for binding the upper and lower wefts against the stuffer warps.

3. An Axminster pile fabric having the pattern visible at the back and formed of stuffer warps all laid in a single plane, wefts laid 90 above and below the stuffer warps and arranged with twice as many wefts below the stuffer warps as above them, a row of pile forming yarns looped about one lower weft and having a second lower weft laid at 95 one side of the row of pile yarns and an upper weft laid at the opposite side of said row, and chain warps for binding the upper and lower wefts against the stuffer warps.

4. A two plane pile fabric having the pattern visible at the back and formed of stuffer warps, wefts laid above and below the stuffer warps and arranged with twice as many wefts below the stuffer warps as above them, a row of pile forming yarns looped about 100 one lower weft and having a second lower weft laid in contacting relation with one side of the row of pile yarns and an upper weft laid at the opposite side of said row, and chain warps for binding the upper and 105 lower wefts to the stuffer warps and against the opposite sides of the row of pile yarns in 110 diagonal relation thereto.

5. A two plane pile fabric having the pattern visible at the back and formed of stuffer 115 warps, wefts laid above and below the stuffer warps and arranged with twice as many wefts below the stuffer warps as above them, a row of pile forming yarns looped about one lower shot of weft and having a second lower shot 120 of weft laid against said row and an upper shot of weft laid against the opposite side of said row, and chain warps passing alternately over one upper shot of weft and under two lower shots of wefts.

6. A two plane pile fabric having the pattern visible at the back and formed of stuffer warps, wefts laid above and below the stuffer warps and arranged in three shot cycles with 125 one shot above and two shots below the stuffer 130

warps, a row of pile forming yarns looped about one lower weft of a cycle and laid against the other lower weft of the cycle and having the upper weft of this cycle laid 5 at the opposite side of said row, each of said wefts being formed of two weft threads, and chain warps passing over the upper weft and under the two lower wefts of a cycle and adapted to hold the two threads of the upper 10 weft in a horizontal plane and the two threads of each lower weft in a vertical plane.

7. A pile fabric having the pattern visible at the back and formed of stuffer warps all laid in a single plane, wefts laid above and 15 below the stuffer warps and arranged with twice as many wefts below the stuffer warps as above them, a row of pile forming yarns looped about one of a pair of lower wefts and having two stuffer warps between each 20 pair of pile forming loops, and a chain warp laid between said two stuffer warps and around the upper and lower wefts.

In testimony whereof, I have signed my name to this specification.

JOSEPH FRANCIS FLORCZYK.
